BOX

Nathan Tufts, Greenfield, Mass., assignor to The
New England Box Company, Greenfield, Mass.,
a corporation of Massachusetts

Application November 12, 1930, Serial No. 495,020

4 Claims. (Cl. 217—12)

This invention has to do with an improved form of box and method of making the same. Boxes of various sorts have been made for some time in such a way that they may be shipped in large bundles in a flat or knocked-down condition. A great deal of space is thus saved in the shipment of the boxes from the point of manufacture to the point at which they are to be used for the packing of commodities of various kinds. At 10 the point of use the boxes are assembled and the sides and ends fastened together in some suitable way.

It has been a primary object of the present invention to provide an improved box construction of this sort which is relatively inexpensive and yet is strong and capable of withstanding the strains to which such boxes are normally subjected when shipped in a loaded condition. The box contemplated, furthermore, is light and easy 20 to assemble at the point of use and is tight at all of its corners so as to prevent leakage of even relatively small commodities. At the same time the contents of the box are protected from dust and rain and the like due to the provision of tight 25 corners. The box is not air-tight, however, so that it may readily be employed in the shipment of fresh fruits which require a certain limited supply of oxygen in the course of ripening. With these ends in view the box is made up completely 30 of wood, fibre-board, binding wire, and staples. It is of such construction, furthermore, that it may be readily produced at a rapid rate on suitable box-forming machinery.

The invention is principally concerned with 35 the production of relatively large boxes such as are commonly designated packing boxes and which must be of sufficiently sturdy construction to withstand the rough usage to which they may be subjected. The provision of metal corner elements joining the side walls of a box has been 40 suggested heretofore but boxes so constructed are objectionable for various reasons. They are relatively expensive and heavy and are difficult to fold into the proper form for use so that they are 45 not readily adaptable for shipment in a knocked-down condition. Furthermore, these boxes do not provide for adequate strength along the side walls unless they are made excessively heavy and 50 bulky. The box contemplated by the present invention overcomes all of these difficulties.

Other features and advantages of the construction will appear from the detailed description which will now be given of one illustrative form of 55 box embodying the present invention. In the

drawing which discloses an illustrative embodiment of the improved box,

Figure 1 is an exterior view of the four sides of the box in knocked-down or flattened condition.

Figure 2 is a view of the inner side of the box 60 in similar condition, and

Figure 3 is a perspective view of the assembled or folded box.

In order to provide a durable, light and inexpensive construction, the sides of the box are 65 preferably formed of thin wood, such as re-sawed lumber, ply-wood, or veneer of suitable thickness. The sides may be made of any suitable dimension, depending upon the size of the box to be produced. If the end of the box is square, 70 then all of the sides will be of the same form and dimension but if a rectangular form is desired, then the sides 10 and 12 will be alike, as will also the sides 11 and 13 but the sides 10 and 11 will be of different width. In the construction of the 75 box the sides when laid flat will be spaced a slight distance apart so as to permit them to be readily folded in the course of assembly. A small crack would then normally be provided along each of the corners of the box. Over these 80 spaces or cracks, between the side members, there is placed a series of strips 14, 15 and 16 of suitable pliable and tough material, preferably fibre board or material of similar characteristics. This material is comparatively light and inexpensive 85 but at the same time is sufficiently rigid or stiff and durable to materially add to the strength of the box as a whole. A crease or fold is preferably formed in the strips along the line which is directly above the space between adjacent side 90 members. This insures ease of bending or folding of the composite sheet when it is desired to assemble the same into a finished box at the point where it is to be loaded. A similar strip 17 of fibre board, or the like, is placed longitudinally 95 over the free edge of one of the sides, such as the side 13. It will be understood that this strip, when the box is assembled by the folding of the composite member, will also overlap the free edge of the side 10 and provide a construction 100 similar to that at the other corners along the meeting edges of the sides 10 and 13.

A number of binding wires 18 are laid transversely across the side members 10, 11, 12 and 13 and the corner strips or members 14, 15, 16 and 17, in the manner best shown in Figure 1, and these wires are extended slightly beyond the free edges of the sides 10 and 13 so as to permit the ends to be twisted together in the assembly of the box at the point of use. A series of staples, 110

or similar fastening elements 19 may be provided to attach the binding wires to the several side members of the box, as well as to the corner members. Some of these staples will not only be passed through the side members but will be passed through the corner members as well, thus serving to unite all of the members into a common unitary structure. No separate means need be provided for attaching the corner members 14, 15, 16 and 17 to the side members 10, 11, 12 and 13 inasmuch as the staples and the binding wires will serve adequately to unite these parts. If desired the corner members may be glued to the side members but the use of any such additional fastening means is unnecessary and would merely add to the expense of the construction of the box.

On the inner sides of the side members 10, 11, 12 and 13, there are arranged at opposite ends of the same a series of cleats 20 of suitable dimension, preferably having mitered ends, as indicated at 21 in Figure 3, so that when the box is folded together in the assembly of the same a complete square or rectangle is formed at the end of the box. The cleats 20 may very readily be secured to the side members simply by means of the staples or similar fastening elements 19 which are employed to secure the uppermost and lowermost binding wires 18 to the box structure. Other fastening means, such as glue or the like, may be employed if desired but this is unnecessary and would merely serve to add to the expense of the construction.

It will be understood that in the formation of the box, either by hand or on a suitable box-forming machine, the several elements employed in the construction of the continuous mat constituting the four sides of the box will be assembled in appropriate positions and then joined by means of the staples. Thus, the cleats 20 will be arranged in line at the opposite ends of the series of side members 10, 11, 12 and 13 and the corner members or strips 14, 15, 16 and 17 will be placed in position in the manner indicated. The series of wires 18 will then be laid out across the several sections and strips and the staples will be driven in to unite all of the parts in the manner explained.

The two ends of the box may be formed of wood boards 22 of suitable thickness and dimension which may suitably be secured to the cleats 21 by a few small nails or similar means.

In the assembly of the box, the free ends of the wires 18 will not be twisted together and the corner strips 17 will not be fastened to the edge of the side member 10 until after the contents of the box has been introduced. As soon as the box has been loaded, any suitable means may be provided for stapling the free edge of the corner element 17 to the side member 10 and for twisting the free ends of the wires.

A box constructed in accordance with the foregoing will be extremely sturdy even though the material of which the sides are formed may be relatively thin. The series of binding wires 18 will lend considerable support and the tough fibre-board strips at the corners of the box will add reinforcement at these normally weak points.

A modified form of construction might be employed in which the main body of the box would be formed of a continuous sheet of fibre-board and the corners would be reinforced by strips of ply-wood, or the like, all bound together in substantially the same way by means of binding wire. However, a construction of this sort

would be more expensive than that first described inasmuch as fibre-board of sufficient thickness to provide a box of the same strength as a given box of the first described type is more costly than the sheets of ply-wood or veneer, or the like, required in such a box and the labor costs are higher in the production of the modified form of box. Furthermore, the suggested modified form of construction would not be as rigid and sturdy as the form first described.

Another modification which might be adopted would be to place the corner strips of fibre-board on the interior sides of the members 10, 11, 12 and 13. In this way merely the ply-wood or similar construction would be exposed on the interior of the box. The staples for the binding wire would in this arrangement also serve to unite all of the parts of the box; the corner strips extending preferably under the cleats would additionally be held in place by the latter. If desired the wires 18 might be omitted entirely in the construction of the box. The staples could be employed in the usual way to secure the strips of thin wood, either ply-wood, veneer or re-sawed lumber or the like, and the strips or sheet of fibre-board as

well as the cleats. In the assembly of the box a few small nails could then be employed to hold the sides in properly folded or assembled position and after the box has been packed it may be reinforced to any extent desired by the provision of either round or flat strapping which will surround the box at selected points. It will be clear that in this type of construction the fibre-board at the corners of the box will serve to unite the sides together into a single mat. An advantage of this type of construction is that it permits the box to be used more readily again after it has been unpacked. The unstapled wires or straps may be readily replaced after the box has been repacked.

Obviously the number of binding wires or straps and rows of staples used in any of the forms of the box explained may be varied to suit the particular requirements.

While the preferred form of construction of the box has been set forth in considerable detail and certain modifications have been suggested, it will be understood that other variations may be made within the scope of the present invention.

What I claim is:

1. A packing box adapted to be shipped in knocked down but assembled condition which comprises four sides of thin wood, tough, rigid fibre-board strips bridging the corners formed between adjacent sides of thin wood and extending substantially the full length of said corners, and wire binding members stapled to said sides and strips and serving as the primary means to secure said strips to said sides.

2. A packing box adapted to be shipped in knocked down but assembled condition which comprises corner members extending longitudinally of the box formed of tough, stiff but bendable fibre-board, thin wood sections at the sides of said box secured to said corner members and binding wire stapled to said members and sections to reinforce the same, said wire and stapling serving as the primary means to hold the parts together.

3. A packing box adapted to be shipped in knocked down but assembled condition which comprises corner members extending longitudinally of the box formed of tough, stiff but bendable flexible fibre-board, thin wood sections at the sides of said box secured to said corner members, cleats carried by the sides of the box adjacent each end, binding wire surrounding said box

adjacent each end, and staples for simultaneously securing together said members, sections, cleats and binding wire, said staples forming the primary securing means for said elements.

5 4. A packing box adapted to be shipped in assembled but knocked down condition formed of tough, stiff but bendable fibre-board and thin wood, the fibre-board being bent to form an angle

providing a tight joint along the full length of each of the corners between adjacent sides, said corners being reinforced by the superposition of fibre-board and thin wood adjacent the same, and binding wires surrounding the box, said thin wood and fibre-board being secured together to form a single mat by said wires and rows of staples.
